(57) **CLAIM**

The ornamental design for a container for defibrillator pads, as shown and described.

DESCRIPTION

FIG. 1 is a top perspective view of the container for defibrillator pads in a closed condition.

FIG. 2 is a bottom perspective view of the container for defibrillator pads of FIG. 1.

FIG. 3 is a front view of the container for defibrillator pads of FIG. 1.

FIG. 4 is a rear view of the container for defibrillator pads of FIG. 1.

FIG. 5 is a right side view of the container for defibrillator pads of FIG. 1.

FIG. 6 is a left side view of the container for defibrillator pads of FIG. 1.

FIG. 7 is a top view of the container for defibrillator pads of FIG. 1.

FIG. 8 is a bottom view of the container for defibrillator pads of FIG. 1.

FIG. 9 is a top perspective view of the container for defibrillator pads in an open condition.

FIG. 10 is a bottom perspective view of the container for defibrillator pads of FIG. 9.

FIG. 11 is a front view of the container for defibrillator pads of FIG. 9.

FIG. 12 is a rear view of the container for defibrillator pads of FIG. 9.

FIG. 13 is a right side view of the container for defibrillator pads of FIG. 9.

FIG. 14 is a left side view of the container for defibrillator pads of FIG. 9.

FIG. 15 is a top view of the container for defibrillator pads of FIG. 9; and,

FIG. 16 is a bottom view of the container for defibrillator pads of FIG. 9.

The portions of the container for defibrillator pads shown in broken lines form no part of the claimed design.
